UNITED STATES PATENT OFFICE.

GEORGE A. FEDER, OF BELLEVILLE, ILLINOIS.

WIRE WINDING AND DISTRIBUTING MACHINE.

SPECIFICATION forming part of Letters Patent No. 543,471, dated July 30, 1895.

Application filed April 22, 1895. Serial No. 546,627. (No model.)

To all whom it may concern:

Be it known that I, GEORGE A. FEDER, a citizen of the United States, residing at Belleville, in the county of St. Clair and State of Illinois, have invented certain new and useful Improvements in Wire Winding and Distributing Machines, of which the following is a full, clear, and exact description, reference being had to the accompanying drawings, forming a part hereof.

My invention has relation to improvements in wire winding and distributing machines; and it consists in the novel arrangement and combination of parts, more fully set forth in the specification and pointed out in the claims.

In the drawings, Figure 1 is a plan view of my complete invention. Fig. 2 is a side elevation thereof. Fig. 3 is a middle vertical longitudinal section on the line $x-x$ of Fig. 1. Fig. 4 is a detail section on $y-y$ of Fig. 1, taken through the brake controlling the reel-shaft; and Fig. 5 is a detail section, showing the mounting of the main driving-wheel.

The present device is an improvement on the wire winding and distributing machine described in Letters Patent of the United States granted to me on April 2, 1895, and numbered 536,782, and has for its object to simplify the construction therein set forth, dispensing among other things with the friction-clutch secured to the main shaft and by which the rate of rotation of said shaft is controlled.

In my present device the variable rotation of the reel-carrying shaft is controlled by a brake mechanism operating against the reel-shaft, and is further controlled by varying the weight of the machine as a whole.

In detail the machine may be described as follows:

Referring to the drawings, 1 represents the frame of the machine, at one side of which is mounted a wheel 2 carried by an ordinary axle, and on the opposite side is mounted a drive-wheel 3 on a short shaft 4, having its bearings in depending blocks 5. Formed integrally with or secured to the hub of the drive-wheel 3 is a gear-wheel 6, which meshes with the terminal removable pinion 7 of the transverse reel-shaft 8, having bearings in the standards 9 and 10 above the frame of the machine. To the shaft 8 is keyed the reel or drum 11. One end of the shaft is embraced

by a pivoted brake shoe or plate 12, between the free end of which and the projecting arm 13 of the standard 10 is interposed a washer 14, the parts being secured by a bolt 15 passing through them. When the washer 14 is in place, as indicated in Fig. 4, the brake-shoe is out of actual contact with the shaft 8, but if the washer be removed and the free end of the brake-shoe be screwed down it will grip the shaft 8 and thus increase the friction against it during the rotation of said shaft. As stated above the pinion 7 is removable, being temporarily keyed to its shaft in any convenient mechanical manner.

On the side of the machine adjacent to the drive-wheel 3 is a box 16, adapted to receive weights—such as rocks, stones, and the like—for a purpose to be presently referred to. Along the forward and rear sides of the frame are disposed a series of outwardly-projecting forks 16' provided with aligning openings for the insertion of pins 17. Between the members of the forks can be temporarily inserted the detachable cross-bar 18, to which the shafts 19 are secured at either end. One end of the bar 18 has a round opening through which the pin 17 at that end is inserted to hold the bar in place between the members of the fork at that end, and throughout the remaining portions of the length of the bar are disposed elongated openings 20 for the reception of the remaining pins 17. The openings 20 are elongated, so that no time may be lost in assembling the parts, as in attempting to insert the pins into circular openings the latter might not always be in alignment with the openings of the fork members.

As seen in Fig. 1, the cross-bar 18, with its shafts 19, can be removed and transferred to the opposite side of the machine, depending, of course, upon the direction the machine is intended to be run. On either side of the machine may be disposed the vertical wire guide-bars 21, inserted temporarily into pockets or sockets 22, said bars having rounded faces to insure the easy passage of the wire past them.

In unwinding the wire the machine is driven in the direction shown by the arrows in Figs. 1 and 2, the pinion 7 is taken off its shaft, and the brake-shoe 12 is clamped more or less firmly against the reel-shaft by removing the washer 14 and binding the free end of the

shoe by the bolt 15. In this way sufficient friction will be applied to the reel-shaft by the brake-shoe, and thus prevent the too rapid unwinding of the wire from the drum. On the other hand, in winding the wire on the drum the machine is driven in the opposite direction, the washer 14 is placed back between the brake-shoe and the reel-shaft bearing to allow the shaft to rotate freely, the pinion 7 is placed back on its shaft, and in case the wire is intended to be wound very tightly and the ordinary weight of the machine be insufficient to accomplish the purpose of winding the drum without causing the drive-wheel and the entire machine to slip on the ground, the device can be additionally weighted down by placing rocks or other weights into the box 16.

Of course the addition of rocks or similar ballast is resorted to where unusual tension is to be imparted to the wire, a purpose for which the ordinary weight of the machine would be insufficient.

As indicated in Fig. 1, the wire can be wound from the opposite end of the reel either by reversing the reel on its shaft (from which of course it can easily slip off) or by starting the wire from that side in the first place, these conditions depending on the relative position of the machine with reference to the fence or other object along which the distribution of the wire is to take place. Thus it is seen that the motion of the reel-shaft is controlled directly either by varying the friction against it by the application of a brake-shoe, or, on the other hand, by varying the weight of the machine as a whole.

In winding up the wire to prevent the interference of the same with the movement of the horse, the bar 18, with its shafts, is shifted to one side, as seen in dotted lines to the left of Fig. 1. The animal in this instance is hitched of course to one side of the center line of the machine.

Having described my invention, what I claim is—

1. In a wire winding and distributing machine, a suitable frame, drive wheels mounted on said frame, a reel shaft adapted to be tem-

porarily coupled to or uncoupled from one of the drive wheels, a suitable receptacle for receiving variable quantities of ballast, and a brake shoe controlling the rotation of the reel shaft, substantially as set forth.

2. In a wire winding and distributing machine, a suitable frame, drive wheels mounted on said frame, a suitable reel shaft mounted in proximity to the drive wheels, a gear wheel carried by one of the drive wheels, a removable pinion carried by the reel shaft and adapted to be alternately coupled to and uncoupled from the gear wheel carried by the drive wheel, a suitable receptacle for receiving variable quantities of ballast, and a brake shoe carried by the reel-shaft-bearing adapted to exert variable pressure on the reel shaft, substantially as set forth.

3. In a wire winding and distributing machine, a suitable drive wheel, a reel shaft adapted to co-operate with the same, and a suitable receptacle carried by the frame for receiving variable quantities of ballast, thus varying the weight of the machine frame for correspondingly varying the tension of the wire on the reel during the draft of the machine along the ground, substantially as set forth.

4. In a wire winding and distributing machine, a suitable frame, drive wheels mounted in the same, a gear wheel secured to one of said wheels, a reel shaft, a removable pinion carried by said shaft and adapted to mesh with the gear wheel, a brake shoe pivoted to one of the bearings of the reel shaft, a removable washer interposed between the free end of the brake shoe and the reel-shaft bearing and adapted when in place to keep the brake shoe out of actual contact with the reel shaft, a suitable receptacle for receiving variable quantities of ballast, and means for securing the parts, substantially as set forth.

In testimony whereof I affix my signature in presence of two witnesses.

GEORGE A. FEDER.

Witnesses.
